UNITED STATES PATENT OFFICE.

MARTIN L. METZGER AND ALBERT COOPER, OF HARRISBURG, PENNSYLVANIA, ASSIGNORS TO WILLIAM O. HICKOK, OF SAME PLACE.

RULING-MACHINE.

SPECIFICATION forming part of Letters Patent No. 316,990, dated May 5, 1885.

Application filed March 17, 1884. (No model.)

To all whom it may concern:

Be it known that we, MARTIN L. METZGER and ALBERT COOPER, citizens of the United States, residing at Harrisburg, in the county 5 of Dauphin and State of Pennsylvania, have invented new and useful Improvements in Ruling-Machines, of which the following is a specification.

This invention relates to certain new and 10 useful improvements in ruling-machines; and it has for its objects, first, to provide means whereby paper may be so regulated in passing through the machine that the successive sheets shall lap or immediately succeed each other, so 15 that each succeeding sheet shall pass under the pens just as the lines of the preceding sheet are finished, whether they extend over a whole or a portion only of that sheet, and this in order to present unruled paper to the pens 20 without having a gap appear between the successive sheets, and consequently cause the pens to run over and saturate the apron or make it necessary to elevate them to ride over such gaps, either of which entails loss of working- 25 time of the machine; second, to provide means whereby the machine shall be capable of ruling a given number of lines of a predetermined length simultaneously with the ruling of two or more other lines varying in length from 30 those whose measurement is predetermined, and also varying with respect to each other; third, to combine a variable-power transmitter with a cam-head on the pen-cylinder shaft for actuating the pen-beam carrying the nest 35 of pens; fourth, to combine such power-transmitter with cams for actuating the stop-gate at predetermined intervals, whereby the succession of the sheets of paper to the pens is predetermined; fifth, to combine such power- 40 transmitter with the shaft carrying the cam-heads for actuating the auxiliary pen-lifters for effecting a variation in the length of the lines.

In the accompanying drawings, forming a 45 part of this specification, and on which like letters of reference indicate the same or corresponding features, Figure 1 represents a plan view of our improved ruling-machine; Fig. 2, a side elevation of the same with a portion of one of the side beams broken away;

Fig. 3, a vertical sectional view of the same, taken on the line X X of Fig. 1, looking in the direction of the arrow; Fig. 4, a view showing a portion of the machine partly in elevation and partly in vertical section, taken on the 55 line Y Y of Fig. 1, looking in the direction of the arrow; Fig. 5, a vertical diametrical sectional view of the power-transmitter, the yoke which supports the same, the cams for actuating the stop-gate, and the several intermediate devices; Fig. 6, a detached enlarged side elevation of a portion of one of the upper power-transmitting disks, of the lower disk, the cams, and the tripping device and shaft which actuate the stop-gate, and the pinion 60 which transmits power to the cam-heads shaft; Fig. 7, a detached enlarged perspective view of the cam-heads for actuating the auxiliary pen-lifters, the pen-lifters themselves, and the stop-gate; Fig. 8, an enlarged detached perspective view of one of the pen-lifter arms and a pen-lifter; Fig. 9, a detached enlarged edge view of the upper portion of the power-transmitter, showing the scale for ascertaining the proper adjustment of such mechanism to actuate the stop-gate to rule a line of predetermined length; Fig. 10, a diametrical sectional view of a portion of the upper and lower power-transmitting disks; Fig. 11, a 65 vertical sectional view of the clamp for connecting the pen-lifters with the rods which support the same; Fig. 12, a front view of such clamp, showing a lifter in cross-section; Fig. 13, a vertical sectional view of the upper portion of the metallic frame, and Fig. 14 a 70 transverse sectional view of the supplemental pen-clamp.

The letter A designates the frame upon which our improved machine is mounted, the same being constructed of wood and of the ordinary type. At the head of the machine are mounted in suitable bearings the feeding and apron rollers B and C, the former being provided with a series of peripheral grooves, in which the usual guide-cords are designed to 75 run. These rollers are provided at one end with gear-wheels D and E, which intergear with each other, and the upper of which receives motion from a drive-pulley mounted on its shaft substituted for the crank shown. By 80 85 90 95 100

this means, it will be observed, rotary motion is imparted to the feeding and apron rollers in opposite directions, whereby the paper is drawn into the machine. A shaft, G, is mounted on the upper portion of the metallic frame, to be hereinafter mentioned, and is provided with a gear, F, which meshes with the gear D, whereby motion is imparted to the power-transmitter, as will presently appear.

10 The letter H indicates the apron, upon which the paper rides through the machine, and which in the present instance passes around the pen-cylinder I, mounted rigidly upon the transverse shaft J, which has its bearings at 15 either side of the frame. The motion of the apron is in the direction of the arrow, (see Fig. 3,) and by reason of frictional contact with the pen-cylinder I causes the same to rotate with it. This apron in practice usually 20 extends to and around a supporting-roller mounted in bearings at the tail of the machine, but which is unnecessary to be shown, as it forms no part of our invention.

In order to adjust the apron H to the proper 25 tension, we provide the depending brackets K, secured at a convenient point to the side of the frame, and provided with a slot in which fits a journal-block, L. This block receives the journal of the tension-roller M, and is adjusted up and down, as circumstances may require, by means of the set-screw N.

In order to prevent the apron from sagging, and to support the same at or near the stop-gate, we further provide a roller, O, mounted 35 in short arms extending from sliding blocks P, which fit within ways Q, secured to the inner face of the side pieces of the frame, and provided with set-screws R, whereby the altitude of said supporting-roller is adjusted.

40 The letter S indicates a metallic frame bolted to one of the side pieces of the frame, in the upper portion of which, as before observed, is journaled a driving-shaft, G. This shaft is provided at the inner end with a gear-wheel, T, which meshes with an idler-pinion, U, mounted on a stud extending from the arm S', pivoted at one end on an extension, S'', of the said upper portion of the frame, and supported at the other, as will presently appear. This 45 pinion meshes with a gear-wheel, V, rigidly keyed to a sleeve, W, to which is also rigidly keyed the disk A', the disk and gear being, however, connected together by screws, and on which is mounted an associated disk, A'', the key B' extending into a key-seat in this disk, whereby the same is capable of movement thereon in the direction of the axis of the sleeve, but is made to move positively with the sleeve in a rotary direction. The 50 sleeve W is mounted for the greater portion of its length within the tubular extension C' of the arm S'. A bracket, D', is secured firmly at one end to the upper portion of the arm S', and is provided with an aperture near the 55 lower end, which receives the hub of the disk A'', whereby said disk and that end of the

sleeve W are given support. To the hub is secured, preferably by means of screws, an internally-threaded block, E'.

In order to adjust the disks A' and A'' to 70 and from each other, by sliding the movable disk A'' to and fro on the sleeve W we provide a binding-rod, F', which passes through said sleeve and block E', the block being screw-threaded, to correspond with the threads on 75 the rod. At one end this rod is provided with a hand-wheel, G', whereby it is actuated, and at the other with a hand jam-nut, H', whereby the same is locked in relation to the block E'. In order, however, to allow of the disks A' 80 and A'' accommodating themselves to any slight unevenness between their inner faces and the exterior surfaces of the disk, to be presently described, we interpose between the sleeve W and hand-wheel G' a washer and spiral spring, I'.

Extending from the frame S is a short stout shaft, J', upon which are mounted the disk K' and the cams L' and M', the two cams being rigidly connected together, and also to the 90 said disk, so that they will rotate synchronously. The periphery of this disk is provided with gear-teeth, and the opposite faces of the same near the periphery are beveled off in lines which converge as they extend outwardly, as more clearly represented in Fig. 10. 95 These beveled surfaces are designed to be quite narrow, measuring them in a radial direction, and the inner or opposite faces of the disks A' and A'' are also beveled in diverging lines from 100 their center outward, the bevel of the respective upper disks agreeing in direction with the narrow bevel-surfaces of the lower disk with which they respectively come in contact. By 105 this means we have ascertained that the upper disks can be so firmly impinged against the lower disk as to cause the latter to rotate positively when the former are rotated, and that with entire smoothness and regularity.

It will appear from what has been said that 110 the upper disks receive rotary motion through the gears V and T' and the pinion U; but in order to vary the speed which these disks transmit to the disk K', and those devices which receive motion from it, it is necessary to adjust the 115 upper disks in a radial direction, so as to bring the point of contact between them and the lower disk at different distances from their center. This is done by providing the frame S with an upwardly-extending portion, S'', 120 having a slot, N', formed therein in the arc of a circle, using the axis of the driving-shaft G as the center therefor. The collar O' is fitted around the tubular extension C' of the arm S', and is formed to snugly fit the slot N'. To this 125 collar is pivotally connected a screw-threaded rod, P', to the upper end of which is fitted an internally-screw-threaded hand-wheel, Q', journaled in the upper end of the extension S'' of the frame S. By this means it will be observed 130 that the upper disks may be adjusted to and from the center of the lower disk, and the speed

imparted to the lower accordingly varied without a variance in the speed of the upper. To maintain these disks in any given position, a washer, R' , and a jam-nut, T' , are fitted over 5 the extension C' , the latter engaging threads thereon, whereby the arm S' is drawn firmly against the extension S'' , and the center of rotation of the upper disks fixed. Now, in order to predetermine the speed at which the 10 lower disk shall be driven, and the relative speed of the other devices which are primarily actuated through said lower disk, we provide a pointer, U' , connecting it with the arm S' , and a graduated scale, V' , mounted stationarily upon a fixed object, in the present instance upon the extension S'' of the frame S . The lines on this scale in the present instance are consecutively numbered 12 to 20, inclusive, and are numbered from 20 to 36, inclusive, 15 of the latter, increasing two at each graduation, and the position of the pointer with respect to this scale will determine the speed of rotation of the disk K' and the consequent frequency of the lifting of the stop-gate, as 20 will presently appear.

As already observed, the periphery of the lower friction-disk, K' , is provided with gear-teeth. A transverse shaft, U' , is journaled to the side pieces of the frame in suitable bearings, and is provided with gear-wheels V' and W' , the former of which meshes with the said disk K' , and receives rotary motion therefrom, while the latter of these gears, W' , meshes with an idler, X' , mounted so as to rotate on 35 a short shaft, Y' , having its bearings in a vertically-slotted bracket, Z' , secured to the lower edge of one of the side pieces of the frame. This idler in turn meshes with a gear-wheel, a , loosely mounted upon the pen-cylinder 40 shaft J , whereby a cam-head, b , is given rotary motion through the instrumentality of the power-transmitter or disks K' , A' , and A'' .

To the gear-wheel a is rigidly connected the cam-head b , the same being also loosely mounted 45 on the shaft J , and being provided with a convenient number of annular recesses and binding-screws, c , to receive and secure the cam-blocks d , which serve to actuate the pen-beam, to be presently described. This beam 50 consists, preferably, of a strip of wood e , provided at one end with a metallic spindle, f , which extends through a block, g , forming part of a vertically-adjustable slide, h , mounted on ways i , formed on the standard j . The 55 foot k of this standard fits in ways formed in the stationary plate l , and is held in a fixed position by a set-screw, m . By this means it will be observed the position of the pen-beam e may be adjusted up and down and in a forward or backward direction at the end of said beam, just described.

The standard j and plate l , as also the set-screw m , are duplicated on the opposite side of the machine, as more clearly represented 65 in Fig. 1, and the upper end of the standard is provided with depending ways n , within

which fits the vertically-adjustable block o , a set-screw, o' , having a head and jam-nut, o'' , serving to adjust it up and down. This block is internally screw-threaded and receives the 70 correspondingly-threaded spindle p , having a head and jam-nut, q .

The adjacent end of the pen-beam is provided with the plate r , having lugs s . A bar, u , is pivoted within the lugs s , as seen in Fig. 75 1, and the spindle p passes through an aperture formed therein. A collar, v , is applied to the end of the said spindle to prevent its drawing out of said block in one direction, and a shoulder, w , formed on the spindle prevents it from slipping too far through the block. By this means the pen-beam is adjusted in a lateral direction to suit individual circumstances, the spindle f sliding back and forth in the block g .

Near one end of the pen-beam e is connected a beam, z , by a binding-screw, a' . This beam is provided with an adjustable weight, b' , having a set-screw, c' , whereby the supplemental arm, to be presently described, for actuating the pen-beam, is counterbalanced, and whereby the degree of pressure of the pens upon the paper is regulated. An actuating-arm, d' , is pivotally connected to the pen-beam e , near one end thereof, and this arm is provided with 95 set-screws e' , whereby the angle of the arm with respect to the pen-beam may be adjusted so as to give the proper inclination to the pens. The foot of the arm d' is provided with a steel contact-plate, f' , beveled off on the under side, and made adjustable by a screw-connection, g' . This plate is engaged by the cam-blocks d as they pass under the same, the lifting of the plate serving to partially rotate the pen-beam e and lift the pens from the 100 paper collectively—that is to say, to lift all the pens simultaneously. As the cam-blocks pass from under the plate f' the pens descend to the paper in a body and recommence ruling.

To the arm d' is connected an interiorly-screw-threaded block, h' , through which passes a threaded adjusting-rod, i' , the same having a head and jam-nut, j' , whereby it is set in a fixed position. The lower end of this rod rests upon a plate, l' , extending from an adjustable bracket, m' , secured to one of the side pieces A . This screw serves to determine the pressure of the pens upon the paper—that is, it fixes a point beyond which the pen-beam cannot oscillate—so that the pens are 110 prevented from being pressed hard against the paper, while the weight b' prevents them from leaving the paper. A lug, p' , is pivotally connected to the bracket m' , and serves to hold the pens above the paper by lifting the arm d' 115 by hand and slipping it under the lower end of the screw i' while the operator is making any given adjustment.

The letter q' indicates the pen-clamp, the same being provided with a tongue, which enters a groove in one edge of the pen-beam e , 120 and is secured in place by one or more set-

screws, r' . A supplemental pen-clamp is provided, consisting of the rabbeted strip s' , secured to the beam e , having a metallic strip, t' , secured to it, and of the bar u' . The bars 5 s' and u' are kept in relative position by the pins w' extending from the latter into the former. These bars are bound together by metallic clamps consisting of plates v' , fitting at one end within the rabbet of the bar s' , and 10 connected at the upper ends by a rod, x' , a set-screw, y' , and washer z' being employed to bind the bars s' and u' together and to hold the extended shank of the long pen. This device is used when it is desired to rule lines of 15 two or more colors, a pen with a long shank in such instance being held by said clamp and extended slightly beyond and between the two pens held by the clamp q' , as seen in Fig. 1.

As an auxiliary means of actuating the pen-beam, we have provided a supplemental arm, 1, similar to the arm d' , as seen in Figs. 1 and 2, the said arm having at one end a plate adapted to be engaged by a cam, to be presently described, and the other end being pivotally connected with a sliding plate, 2, set-screws 3 and 4 being employed to adjust this arm for the same purpose as that ascribed to adjusting the arm d' . A slide, 5, is provided with an extension, 6, having ways 7, with 25 which the slide 5 engages. The slide 5 fits within ways 8, formed on a plate, 9, secured to the pen-beam e , as more clearly seen in Fig. 1.

Referring back to the cam L' , it should be 35 observed that the same is provided with one offset in its periphery, as seen in Fig. 6, while the cam M' is provided with two offsets at two diametrically-opposite points, as also seen in that figure.

40 A rock-shaft, 10, is journaled at one side of the machine in the plate l , as seen in Fig. 1, and at the other side in a bar, 11, connected with the other plate l , as seen in Figs. 1 and 4. To this shaft, near one end, is fastened a 45 short arm, 12, as also seen in Figs. 1 and 4, and is connected with one of the side pieces of the frame by a spring, 13, and rod 14, and binding-post 15, through which the rod passes. The downward movement of the arm 12 is 50 limited by an india-rubber stop, 12^a, held in a socket, 13^a. By this means the tendency of the shaft 10 is to rock in the direction of the arrow, seen in Figs. 4 and 6, which tends to normally lift the stop-gate, as will presently appear, from the apron. A trip, 16, is attached to the shaft 10, and consists, essentially, of a collar having a block, 17, pivotally connected thereto, and carrying a finger, 18, as further described in Letters Patent issued to 55 Hiekk, Cooper, and Brown, January 27, 1880. This finger presses against the one or the other of the cams L' or M' , according to adjustment, and resists the tendency of the spring 13 to rotate the rock-shaft 10. Several short arms, 60 19, are secured to the shaft 10, and are connected with the stop-gate 20, consisting of a bar

having downwardly-extending lugs which normally engage the upper surface of the apron H , these devices being more clearly represented in Fig. 7. Thus it will be observed 70 that when an offset of the cams L' or M' passes upwardly by the finger 18 the same will immediately drop into the depressed portion of the periphery of such cam, and thereby allow the spring 13 to sufficiently turn the rock-shaft 75 10 to lift the gate 20 from the apron and allow a sheet of paper to pass under the same along with the apron. The cam then passes on and the finger rides out upon the regular surface of the same, the shaft is turned back to normal position, and the gate again brought upon the apron, the end of the sheet having in the meantime passed under the gate. 80

We shall now refer to the mechanism which immediately operates the pen-lifters. A pinion, 21, is loosely mounted on the shaft J' and rigidly connected with the cam M' , whereby it receives rotary motion from the friction-disk K' . This pinion meshes with a similar pinion, 22, rigidly mounted on the shaft 23, having a bearing at one end in a bracket, 24, one end of which bracket is supported by a rigid connection with the end of the shaft J' . The other end of the shaft 23 finds its support in the bracket 25, and on this shaft are mounted 90 a convenient number of cam-heads, 26, having annular grooves which receive cam-blocks 27, secured therein by set-screws 28. A rod, 29, is also mounted in the brackets 24 and 25, as more clearly seen in Figs. 1 and 2. To this 100 rod are rigidly connected collars 30, having lugs 31, as clearly seen in Fig. 8. Loosely mounted on the rod 29 are sleeves 32, on the upper surface of which are formed short plates 33, and to a lip, 34, extending from said plate 105 is pivotally connected a pen-lifter-actuating arm, 35. This arm is provided at one end with a contact-plate, 36, with which the cam-blocks 27 on the cam-heads 26 engage, whereby the said arms 35 are depressed. This arm 110 is also provided with adjusting-screws 38, whereby its relative position with the plate 33 is adjusted so as to regulate the lifting and the position of the pen-lifters, as will presently appear. 115

Extending from the sleeves 32 are short legs 39, terminating in boxes 40, having openings extending through the same from side to side and from front to back. In the latter opening is fitted the pen-lifter 41, and in the former 120 are fitted the rod 42 and the block 43, the latter resting upon the upper surface of the pen-lifter, and a set-screw, 44, being employed to bind these several parts together. The lug 31 and the arm 35 have short studs 45 extending 125 from them, over which is fitted an elastic band or other spring, 46, whereby the arm 35, plate 33, and lug 31 are yieldingly held together. Blocks 47, similar to blocks 40, though separate from the legs 39, are fitted to the rods 42 130 and provided with other pen-lifters, 48. It will be observed that an almost indefinite

number of these latter blocks and their pen-lifters may be fitted upon the rod 42, whereby as many pens may be lifted by one cam-head as may be necessary for any particular design.

5 The pen-lifters consist, preferably, of metallic strips extended from the boxes out to and underneath the pens, and may be wide enough at the point to lift one or more pens.

It should be observed that as the collars 32 are mounted loosely on the rod 29, the independent sets of pen-lifter arms 35 may be actuated at different times or synchronously by placing the cam-blocks 27 of the cam-heads 26 in line with each other, or in advance one of 15 the other, so as to engage the plates 36 at different times or in succession. By this means an almost indefinite number of lines of different lengths may be ruled by simply adding 20 additional cam-heads 26 and pen-lifter arms and their immediate devices.

The operation of our machine will be readily understood when taken in connection with the foregoing, and is as follows: Let it be supposed that the paper to be ruled is to have 25 three lines each nine inches long, two lines each eight and one-half inches long, and three lines each seven and seven-eighths inches long. The nine-inch lines being the longest, their length will be determined by the frequency of the raising of the pen-beam entire. In order, then, to produce lines nine inches long, the pointer U' will be set opposite the graduation 18 on the scale D' by actuating the hand-wheel Q'. Then the trip 16, mounted on 30 the shaft 10, is adjusted so that the finger thereof will engage the cam M', having the two offsets. The first of these adjustments will give the disk K' the proper speed to cause the apron to travel nine inches, and 40 consequently to move the paper nine inches under the pens, while half the cam M' in rotating passes the finger 18, the stop-gate during this time being down, so as to prevent the passage of any incoming sheet until the proper time. When the depressed portion of the 45 said cam's periphery reaches the finger, it drops into the same, and thereby allows the spring 13 to lift the stop-gate and allow a succeeding sheet of paper to pass on to the pens. 50 Should the first sheet have been longer than nine inches, then the succeeding sheet would have lapped over that part of the first sheet, yet not beyond the gate when the gate was raised. Thus the second sheet is allowed to 55 accompany the first, and is lapped over that portion of the first in excess of the nine-inch line, which portion usually forms "the head" of the sheet. Thus, also, it appears that the pens will ride upon the second or succeeding sheet just as the lines on the previous sheet are completed, the sheet being fed in "foot" first.

From what has been said it will appear that the gate will be actuated or lifted twice 60 at each revolution of the cam M'. This is done in order to allow the sheets to succeed

each other with sufficient frequency when the longest line to be ruled is less than twelve inches. Therefore, for this we provide the cam with two offsets. When the longest line 70 to be ruled in a given pattern is twelve inches long, or any number more than twelve within the range of the machine, (thirty-six according to the scale in the present case,) the trip on shaft 10 will be placed so as to engage the cam L', which has but one offset, which will be found to allow the spring 13 to actuate the gate with sufficient frequency for 75 lines of that length. The double cam may be used, however, in such latter instance; but the pointer in ruling a line twelve inches, if the double cam is used, would be set opposite the graduation 24 on the scale.

The following is the rule governing the use of this portion of the machine: In ruling 80 lines from six to twelve inches, exclusive of twelve inches, the double cam is used, and the pointer set on the scale at double the number of inches to be ruled. In ruling lines between twelve inches and upward, inclusive of 90 twelve, the double cam may be used, but the single cam is generally used. Now, to resume the example under consideration, a pen-lifter is adjusted under each of the pens which is to rule the line eight and one-half inches 95 long, and the cam-blocks in either of the cam-heads 26 which is to actuate said lifters are adjusted by hand until they lift the lifters at the proper time to make a line of that length. Under each of the pens which are to rule the 100 lines seven and seven-eighths of an inch long a pen-lifter is adjusted, and the cam-head which is to actuate them set in the manner above described.

It is to be observed that when the ruling is 105 to be done on the "lap" system" plan either of the alternative means hereinbefore described—namely, the cam-head on the pen-cylinder shaft, or the cam-head on the shaft 23—is adjusted so as to lift the pen-beam and all the 110 pens entire with it at the proper time to terminate the longest lines being ruled.

When ruling as in the example above given, and the paper passes far enough under the pens to complete the shorter lines, they (the 115 pens) are lifted by their lifters and held up until the paper passes far enough to complete the longer lines, when they again descend to work, the pen-beam entire not being elevated at all, the pens which rule the longer 120 lines running from one sheet onto the foot of the succeeding sheet. When, however, the paper is fed foot first, but is not being lapped, then the same operation takes place as to the pens which are ruling the shorter lines, and, in 125 addition to this, the pen-beam entire is actuated to raise the pens which rule the longer lines, when the paper has passed far enough to complete such lines, and all the pens are thus held from the paper while that part of 130 the same which constitutes the heading is passing under the pens. They all descend

again to the paper when the new sheet reaches them foot first. Again, when the paper is fed in head first and the heading-space is left, the pens entire remain elevated until the paper reaches the point where the longer lines are to commence. When this takes place, the pen-beam tilts and the pens come down to the paper, save those which are to rule the shorter lines, which are resisted by the pen-lifters until the paper passes far enough to present the points of commencement of the shorter lines under the pens. It will be understood that to do this either the cam-head on the pen-cylinder shaft or the cam-head on the shaft 23 is adjusted so as to hold the pen-beam up and let it down at the proper time.

The power-transmitter described in this application forms the subject of another application filed by us.

Having thus fully described our invention, what we claim as new, and desire to secure by Letters Patent, is—

1. In a ruling-machine, the combination, with the variable-power transmitter consisting, essentially, of the engaging frictional disks, of the cam-head having a gear-wheel attached thereto and mounted upon the pen-cylinder shaft, an idler meshing with said gear-wheel, and the shaft carrying two gear-wheels meshing, respectively, with one of the disks of the power-transmitter and with said idler.

2. In a ruling-machine, the combination, with the power-transmitter consisting, essentially, of the engaging disks constructed to be radially adjusted with respect to each other so that any predetermined velocity of speed may be transmitted, of the stop-gate actuated thereby, whereby the time of the elevation of the said gate may be predetermined.

3. In a ruling-machine, the combination, with the frictional variable-power transmitter, and one or more cams actuated thereby, of the stop-gate, its shaft constructed with a normal tendency to elevate the gate, and the trip device mounted thereon to engage with either of said cams to hold the gate to the apron and release it at a predetermined time.

4. In a ruling-machine, the combination, with the two disks capable of being adjusted one from the other and mounted upon the adjustable shaft, and a third disk constructed to extend between and be engaged by the said two disks, of one or more cams rotated thereby, and the stop-gate, its shaft, the arm and the spring normally tending to elevate the gate, and the trip device on the shaft to engage either of said cams.

5. In a ruling-machine, the combination, with the frictional power-transmitter consisting, essentially, of the engaging frictional disks, of the pen-lifters and the intermediate devices, substantially as described, for actuating the same.

6. In a ruling-machine, the combination, with the frictional variable-power transmitter consisting, essentially, of the engaging

frictional disks, of the cam-heads actuated thereby, the arms constructed to be actuated by the cam-heads at one end, and to carry one or more pen-lifters at the other end, and the pen-lifters.

7. In a ruling-machine, the combination, with the two disks, one capable of being adjusted to and from the other and mounted upon an adjustable shaft, and a third disk constructed to extend between and be engaged by the said two disks, of the cam-shaft carrying cam-heads capable of being set with the blocks in line or in advance of each other, gears gearing said shaft with the third disk, the independently-mounted pen-lifting arms, and the pen-lifters carried thereby, the respective sets of which are capable of being actuated synchronously or successively.

8. In a ruling-machine, the combination of a plurality of pen-lifter-actuating arms mounted upon a single rod, each independent of the other, and carrying one or more pen-lifters.

9. In a ruling-machine, the combination, with the pen-lifter-actuating arm having a box at one end, of the rod held thereby, and the independent blocks and pen-lifters secured to said rod.

10. In a ruling-machine, the combination, with the pen-lifter-actuating arms independently mounted upon a single rod, and carrying each one or more pen-lifters, of the cam-heads to actuate the arms synchronously or successively.

11. In a ruling-machine, the combination, with the frictional power-transmitter consisting, essentially, of the engaging frictional disks constructed to be radially adjusted with respect to each other, so that any predetermined velocity of speed may be transmitted, the cam-head actuated thereby for operating the pen-beam, one or more cams rotated by said power mechanism, the stop-gate actuated by either of said cams, the independently-mounted pen-lifter-actuating arms, the cam-heads for actuating said arms and the pen-lifters carried thereby.

12. In a ruling-machine, the combination, with the supporting-rod and the fixed collar having a lug, of the pen-lifter arm loosely mounted on the rod and constructed to be supported by the lug.

13. In a ruling-machine, the combination, with the supporting-rod and the collar fixed thereon and provided with a lug, of the collar loosely mounted on the rod, and the pen-lifter arm pivotally connected with the loosely-mounted collar and provided with adjusting-screws, and constructed at one end to be engaged by an actuating-cam, and at the other to connect with one or more pen-lifters.

14. In a ruling-machine, the combination, with the variable-power transmitter constructed of two disks mounted on the same shaft and having their adjacent faces divergently disposed to each other, and a third disk

having an annular surface on either side thereof and adapted to fit between and be engaged by the said two disks, of the cam-head having a gear-wheel attached thereto and mounted upon the pen-cylinder shaft, an idler meshing with said gear-wheel, the shaft carrying two gear-wheels meshing respectively with the power transmitter and with said idler.

15. In a ruling-machine, the combination, with a variable-power transmitter constructed of two disks mounted on the same shaft and having their adjacent faces divergently disposed to each other, and a third disk having a narrow annular surface on either side thereof and adapted to fit between and be engaged by the said two disks, of the stop-gate adapted to be actuated thereby, whereby the elevation of the said gate may be predetermined.

16. In a ruling-machine, the combination, with the variable-power transmitter constructed of two disks mounted on the same shaft and having their adjacent faces divergently disposed to each other, and a third disk having a narrow annular surface on either side thereof and adapted to fit between and be engaged by the said two disks, of the pen-lifters adapted to be actuated thereby.

17. In a ruling-machine, the combination, with the variable-power transmitter construct-

ed of two disks mounted on the same shaft and having their adjacent faces divergently disposed to each other, and a third disk having a narrow annular surface on either side thereof and adapted to fit between and be engaged by the said two disks, of the cam-heads actuated by the said third disk, the arm constructed to be actuated by the cam-heads and to carry one or more pen-lifters.

18. In a ruling-machine, the combination, with the variable-power transmitter constructed of two disks mounted on the same shaft and having their adjacent faces divergently disposed to each other, and a third disk having a narrow annular surface on either side thereof and adapted to fit between and be engaged by the said two disks, of the cam-head actuated by the third disk for operating the pen-beam, one or more cams rotated by said third disk, the stop-gate adapted to be actuated by said cams, the independently-mounted pen-lifter-actuating arms, the cam-heads for actuating said arms and the pen-lifters carried thereby.
